UNITED STATES PATENT OFFICE.

WALTER EVERETT MOLINS, OF LONDON, ENGLAND.

GUMMING DEVICE.

Application filed July 1, 1925, Serial No. 40,825, and in Great Britain July 11, 1924.

The present invention has reference to improvements in devices for applying adhesive to wrappers, labels, cigarette packages, and the like, and it relates more specifically to 5 apparatus of the type presenting a container for the adhesive substance in which an adhesive-dispensing member, generally in the form of a disc, is rotatably mounted in contact with the adhesive, a portion of the disc 10 projecting from the container and applying thereby the adhesive to the article operated on as required.

My invention has for its object the provision of an improved apparatus of the type 15 stated, particularly, but not exclusively, adapted, for use with automatic cigarette and like packaging machines.

To this end the apparatus is provided with means for ensuring a continuous supply of 20 adhesive by keeping the container outlet clear of grit, dust, or other impurities tending to choke it, with means for applying adhesive to certain portions of the object only, and also with means for effecting a break or 25 interruption in the line or stripe of adhesive which the disc applies to the object, so that when for instance cigarette packages are worked up, a portion at one end thereof is left free of adhesive, which is desired in 30 certain types of folded packages.

According to this invention the adhesive applying disc is rotatably mounted in a container presenting a slot in its wall so that a portion of the disc periphery projects outwardly therethrough into the path of the traveling packages. The disc fits the slot snugly with the exception at the entry end where the slot is enlarged, and at the other end, the edge where the disc emerges, this 35 edge is provided with a small groove or notch which allows the disc to entrain therethrough a thread of adhesive, whereas the portions of the disc circumference flanking this adhesive thread or strip are constantly 40 wiped free from adhesive by the edges of the large slot.

If desired, a special scraper may be provided at the exit end of the wall slot and the small notch then provided in this scraper, as 45 hereinafter described.

A projection of relatively small extent extends peripherally from the disc, which projection is preferably of less width than the thickness of the disc and extends beyond the

disc periphery to the extent of the depth of 55 the small notch through which the adhesive is entrained.

With this arrangement, at each revolution of the disc, its projection serves to clear the notch, and as it is wiped clean by the scraper 60 at the point where it emerges from the bath, it leaves a zone or stripe free of adhesive on the article operated on. Thus, a wrapper held in contact with the disc will receive a 65 continuous line of adhesive until acted upon by the projection, when an interruption in the line will occur as long as the projection is in contact with the wrapper.

In order to make my invention more readily understood, I will now describe it in detail in connection with the accompanying drawings, in which Fig. 1 is a plan of a section of a wrapping machine having the new gumming device applied thereto; Fig. 1^a is 70 a perspective view of a wrapping machine showing the application of the invention; Fig. 2 is a section on line 2-2 of Fig. 1; Fig. 3 is a side elevation of the adhesive container; Fig. 4 shows a package in the course of being gummed; Figs 5 and 6 are 75 top and side views respectively of the scraper, drawn to a somewhat larger scale, and Figs. 7 and 8 show details of a modification.

The improved gummer is shown as applied to the bed plate 2 of a wrapping machine, and the type of packet handled thereby is shown in Fig. 4. In such a machine two identical gumming devices A and B are used, one on each side of the conveyer slot 90 C, the one B only being shown in part in Fig. 1. The packet travels between the two gummers A and B on an endless belt or apron in well known manner.

Each gumming device comprises a container 1 for the adhesive substance, and the container is adjustably mounted on the bed plate 2 by means of the slot and set screw arrangement 3 to accommodate various sizes of packets. In the bottom of the container is fitted the stub axle 4 upon which the applicator disc 5 with its boss 5^a is free to rotate in the direction of arrow D, Fig. 1. The disc 5 projects with part of its periphery through a slot 11 in the container wall, 105 which slot in the preferred embodiment is enlarged at the end E (Fig. 3) where the disc enters the container. At the other end

F the disc makes a close fit with the slot. This enlargement at E is provided for the purpose of preventing adhesive being scraped off the disc at this point where it would accumulate and then soil the passing packets. Into a peripheral groove 12 in the disc 5 a segment 13 of hard metal or the like is fixed slightly projecting around the disc rim. At the exit end of the slot 11, at F, a 10 scraper 14, preferably of brass, is mounted and this scraper is provided with a notched or bifurcated resilient scraper finger 15 through which the disc projection 13 can pass with wiping contact, the tines of the 15 scraper making wiping contact with the rim of the disc.

The applicator disc may be driven in any suitable manner. As shown, by way of example, it is driven from a main shaft 7 by 20 means of bevel gears 6 and 8, which latter is fixed to the shaft 9 whose other end extends into a recess in the boss 5^a, where it is secured by the set screw 10. With this arrangement the upper driving gear as a whole may be 25 lifted for removing the disc and container for cleaning or other purposes. In the machine organization shown in Fig. 1^a C' are conveyor pieces, only one of which is shown, which travel along the slot C. Wrapping 30 material M is fed downward through a slot m in the bed plate 2 and the article to be wrapped is carried through it into the folding apparatus N, which folding apparatus is of standard form and well known in the art; 35 the adhesive containers 1 with their rotating disks 5 are shown in their working relationship and it will be seen that the disks project through slots in the folders o; and electric heaters p, serving as guides and otherwise, lie in the path of travel of the folded and gummed packets, whereby the applied adhesive is quickly dried.

In operation the disc 5, rotating in the direction of arrow D (Fig. 1), entrains on 45 its rim a thread of adhesive equal in cross-section to substantially the conformation of the small slot or opening between the tines of the scraper finger 15, the remaining portions of the rim have been wiped clean by 50 the tines, thus leaving on the rim only a narrow streak or thread of adhesive, as described. The segment 13, however, in passing through the cut-out is wiped clean also and will therefore simply contact with 55 the packet without transferring adhesive thereto.

By adjusting the position of the segment 60 13 on the disc 5 and timing thereby its passing relative to the movement of the packet past the gumming device, it is possible to apply adhesive to the packet only where it is needed.

In the packet P, shown in Fig. 4, the top flap T of the wrapper is about to be turned 65 down, after adhesive has been applied in a

line Q to the lower flap R. As in this instance adhesive is not wanted on the part S, the applicator disc has been accurately timed to give this result.

It may be found necessary to provide the 70 disc with more than one segment 13, if for each revolution of the disc several interruptions in the gumming operation are required. If no interruption in the adhesive line is 75 wanted, the segment 13 is to be replaced by a small pin which then acts as a wiper to periodically clear the slot in the scraper 15 and prevent the slot from being clogged with adhesive.

In a modification I may dispense with the 80 scraper 14 and the cut-out 15 (Figs. 7 and 8) in which instance sufficient clearance must be left between the rim of the applicator disc and the slot 11 to allow the adhesive to pass by the projecting segment or segments 13 on the disc, making a lightly wiping contact with the slot edge as it is of the width of the disc and contacts above and below with the slot edge.

What I claim is:—

1. Apparatus for applying adhesive for the purposes described, comprising an adhesive receptacle, a disk rotatably mounted to permit the periphery thereof to take up adhesive material from the receptacle, a scraper operative to remove excess adhesive from the periphery of the disk, and an interrupting projection upon the periphery of the disk and adapted in the rotation of the disk to periodically wipe against said 100 scraper.

2. Apparatus for applying adhesive for the purposes described, comprising an adhesive receptacle, a disk rotatably mounted to permit the periphery thereof to take up adhesive material from the receptacle, a 105 slotted scraper arranged for engagement with the periphery of the disk to remove therefrom the supply of adhesive except upon that portion alining with the scraper slot, and a projection upon the periphery of the disk adapted in the rotation of the disk to wipe against the scraper for the removal of adhesive from the scraper to keep the slot thereof clear.

3. Apparatus for applying adhesive for the purposes described, comprising an adhesive receptacle, a disk rotatably mounted to permit the periphery thereof to take up adhesive material from the receptacle, and a resilient scraper having spaced tines engaging the periphery of the disk and having spaced tines operative as wipers to remove from the periphery of the disk the adhesive material except along that portion of the 120 disk lying in alinement with the space between the tines.

4. Apparatus for applying adhesive for the purposes described, comprising an adhesive receptacle having a slot in one of its 125

walls, said slot being widened at one end, a disk rotatably mounted in said receptacle to take up adhesive material from the receptacle and having a portion of its periphery projecting outwardly through said slot, the opposed faces of the disk adjacent to the projecting portion of its periphery being in engagement with the walls of the slot at such enlarged end of the slot and lying out of contact with said walls at such end of the slot.

5. Apparatus for applying adhesive for the purposes described, comprising a receptacle having a slot, a disk rotatably mounted 15 in the receptacle so as to take up adhesive material therefrom and having a portion of its periphery projecting outwardly through said slot, and a scraper at one end of said slot arranged to overlie and contact 20 with the periphery of the disk, said scraper having a slot disposed between opposed scraping surfaces thereof, whereby a stream of adhesive of a cross-section equal to the

area of the slot will be allowed to remain upon the periphery of the disk, while the 25 portions of the periphery of the disk on each side of the line of the slot will be scraped free of adhesive by said opposed scraping surfaces of the scraper.

6. Apparatus for applying adhesive for 30 the purposes described, comprising an adhesive receptacle having a discharge slot, a rotary disk mounted in the receptacle and having a portion of its periphery projecting outward through said slot, scraping means 35 on the receptacle for removing excess adhesive from portions of the periphery of the disk, and a segmental interrupting projection extending around a portion of the periphery of the disk arranged for engagement with the scraper for the removal of adhesive from the scraper to keep the slot thereof clear.

In testimony whereof I affix my signature.

WALTER EVERETT MOLINS.
